UNITED STATES PATENT OFFICE.

FRANK S. BARKS, OF ST. LOUIS, MISSOURI.

LUBRICATING DEVICE.

Application filed December 3, 1925. Serial No. 72,898.

This invention relates to greasing apparatus, and with regard to certain more specific features to a portable grease pump which is pneumatically operable.

5 Among the several objects of the invention may be noted the provision of a portable grease pump which is instantly operable to pump quantities of strained grease merely upon manual operation of a valve; the provision of a pneumatic grease pump which is adapted to receive air for its operation from the ordinary pneumatic tire filling air line and valve; the provision of apparatus of the class described which pumps predetermined 10 quantities of grease; the provision of apparatus of the class described comprising in part an improved full-stroke valve gear and cooperating self aligning device; and the provision of a device of the class described 15 which is economical of manufacture, light in weight, yet subject to little or no derangement in operation. Other objects will be in part obvious and in part pointed out hereinafter.

20 The invention accordingly consists of the elements and combinations of elements, features of construction, and arrangements of parts which will be exemplified in the structure hereinafter described and the scope of 25 the application of which will be indicated in the following claims.

In the accompanying drawings, in which is shown one of various possible embodiments of the invention and a modified element therefor.

30 Fig. 1 is a top plan view of the pump, showing parts broken away;

Fig. 2 is a longitudinal vertical section taken on line 2—2 of Fig. 1;

35 Fig. 3 is a front elevation of the device showing parts broken away in section;

Fig. 4 is a fragmentary rear elevation of the pump;

Fig. 5 is a vertical lateral section taken on 40 line 5—5 of Fig. 2;

Fig. 6 is a side elevation of a control valve with parts broken away;

Fig. 7 is a front elevation of the control valve showing parts broken away;

45 Fig. 8 is a fragmentary section showing a modified form of plunger bearing; and

Fig. 9 is a diagrammatic plan view showing in solid lines the arrangement of various parts while in use, and in dotted lines shows 50 the arrangement of certain parts when the device is not in use.

Similar reference characters indicate corresponding parts throughout the several views of the drawings.

Referring now more particularly to Figs. 1 and 2 of the drawings, there is illustrated at numerals 1 and 3 a pair of longitudinal side frames or rails. Each of the frames or rails 1 and 3 is formed with a leg 5 at the front and rear and each leg 5 is provided with a swivel caster 7. The casters 7 are adapted to stay with the legs 5, when the device is picked up as will be hereinafter described.

The rails 1 and 3 are provided with upper 70 horizontal flat and/or machined surfaces 9 for the purpose of receiving bolted thereto, at the forward ends, a laterally formed pump casting 11. Rearwardly the surfaces 75 9 of the frames 1 and 3 have bolted thereto a laterally formed engine casting 13. The frames 1 and 3 and castings 11 and 13 form a unit. For stiffening purposes a cross-bolt 14 and spacer 16 (Figs. 1 to 3) are provided laterally between and centrally of the 80 side frames. This stiffening device may be dispensed with in small sizes of the pump.

Between the castings 13 and 11 and rails 1, 3 respectively, are held bolted sidewardly 85 extending oppositely placed horns or hose clips 15 for the purpose of holding cradled therein the delivery line when not in use as will be further made clear.

Held also to opposite sides of said castings 11 and 13 is a handle or grip 17, by 90 means of which the greasing device as a whole may be lifted and transported about.

Bored lugs or ears 19 on the rear of the side frames 1 and 3 are adapted to rotatably receive a forged handle-bar 21 for purposes 95 of drawing the pump about. The handle-bar 21 is forged with downward extensions 23 which engage a pair of the said legs 5 of the rails 1 and 3 and prevent descent of the bar to the floor when said bar is not in use 100 (see Figs. 2 and 9).

Referring now more particularly to the forward pump casting 11, it may be seen that said casting comprises flanges 25 whereby it is bolted to the side frames 1 and 3, 105 as described. Longitudinally and centrally of said flanges and formed therewith is a bored plunger cylinder 27 provided at its forward end with a conventional ball check valve 29. As indicated in Fig. 2, the rear end of said plunger cylinder may be counterbored to receive a stuffing gland 31, altho 110

in some instances it would be desirable to form said rear end as indicated in Fig. 8, that is, with a plain slide bearing 33. Such slide bearings, where wear is not excessive, do not leak excessively and cannot be tampered with to be put out of operation by tightening a device such as the stuffing gland 31.

Around a more or less central portion of the bore of cylinder 27 is cored an inlet passage or space 35 which leads up to a chamber 37 cast integrally with the bored cylinder 27. The passage 35 communicates with the cylinder 27 at all circumferential points within the length of said passage 35 along the cylinder 27. Bolted to the flanged top of said chamber 37, in grease-tight fashion, is a grease chamber 39. The chamber or container is provided with a lid 41. The bottom 43 thereof is provided with an opening 45 which aligns with the upper opening of the chamber 37 and is adapted to receive the conical rim of a strainer 47 therein.

As will later be made clear, grease and the like is adapted to be drawn or forced from the chamber or container, through the strainer 47, passages 37, 35, bore of cylinder 27, valve 29, to a supply line 49 (preferably flexible) made fast to the outlet end of the valved cylinder 27.

To accomplish the above purpose, a plunger 51 is caused to reciprocate in the bored cylinder 27 so that its forward end crosses and recrosses the space 35. The plunger is made to fit the cylinder 27 snugly and as the plunger recedes rearwardly, the check valve 29 automatically closes. Hence, a vacuum is drawn in the cylinder 27 and as the plunger end recedes over the more or less annular opening 35, grease rushes from all sides of the cylinder 27 and into said cylinder. At the next forward movement of the plunger the grease in cylinder 27 is forced through the check valve 29 and out into the line 49. In starting the device, it may be primed by pouring oil into the passage 35 by way of the container 39. If after a period of operation the device should lose its prime, priming may be accomplished by inverting said device, removing a plug 53 leading to chamber 35 and pouring oil or the like into said chamber 35. This latter method of priming saves the operation of removing grease from the container 39 in order to get oil into the passage 35.

It is clear that the reciprocating action of the plunger 51 may be continued indefinitely to draw grease from the container 39 and discharge it into line 49. In order to reciprocate the plunger, an air engine E is provided at the rear of the device. This driving engine is associated with and cast (in part) with the said casting 13.

The air engine E comprises a work cylinder 55 to which is longitudinally cast, on

center line, a spring retaining cylinder 57. These cylinders are adapted (as a unit) to be aligned on center line with the cylinder 27, at least approximately.

Passing through the cylinder 57 and into cylinder 55 is a piston rod 59. The rod 59 passes out of the forward end of said cylinder 57 and cooperates with the plunger 51 by means of a counter bore and cross pin combination 61. The stated combination 61 is permanent, but during assembly permits of some mis-alignment between the cylinders 55, 57 and 27, in so far as the counterbore in the shaft 59 may be made somewhat larger than the diameter of plunger 51.

At the rear end, the rod 59 is provided with a driving piston 63. The piston comprises a backing plate 65, a leather piston 67 and a clamping cup 69, all held to a shoulder on rod 59 by means of a nut as shown. The cup 69 is flanged out farther than is the piston, so that the relatively soft piston cannot strike the head 71 of the cylinder 55. The piston 63 is normally held to the left or rear end of its cylinder by means of a spring 73 reacting between said piston and the front of cylinder 57.

A driving stem 75 for the valve gear of engine E is supported with regard to, and moves with the piston rod 59. It is so supported for the said movement by screwing the rear end of it into the piston 63 and pinning the forward end into a vertical bracket 77, which bracket is held by means of a tight fit, and set screw 79, to the forward jointed end of the piston rod 59 (Fig. 1). The said rod 75 passes through a proper passage in the head end of cylinder 55 and is steadied by passage through an ear 81 at the front end of the cylinder 57. It is clear that by means of the construction described, the piston rod 59 cannot twist out of its assembled position and a rugged aligning system is provided for driving the valve gear to be described.

A cross-shaped lug 83 is cast on the top of the work cylinder 55. The lug is provided with a longitudinal bore 85 for slidably receiving a valve 87. Positive movement-limiting heads 89 and 91 are provided at the rear and front ends respectively of this valve. The front head 91 serves also to lock a valve stem 93 to the valve.

Vertically drilled across the valve bore 85 are passages 95 and 97 serving inlet and exhaust purposes respectively. These passages are both joined to a cylinder port 99 by way of a common passage 101, which is also drilled, and thereafter end-plugged as shown in the drawings. The passage 101 is interposed between the valve 87 and the interior of cylinder 55. The exhaust passage 97 leads direct to the atmosphere and the inlet passage is provided with a conventional air inlet plug 103.

To bring air to the inlet passage 95 it is only necessary to hold a conventional air nozzle 105 (such as is used for filling automobile tires and available at most garages) to the plug 103. The plug 103 and nozzle 105 mutually open one another and air may flow from the compressed air line 107, associated with said nozzle 105, to the inlet passage 95. The description of the plug 103 and nozzle 105 is not detailed here, inasmuch as their constructions and combination are well known, conventional, and are not claimed herein to be new per se.

In order to hold the nozzle 105 to the plug 103, a hinge block 109 is held to the lug 83 by means of a shoulder on the plug 103. To this block 109 is hinged an adjustable saddle member 111, which is adapted to swing over the nozzle 105 and be clamped down thereon, thereby holding the nozzle in place for delivering air. Wing nuts 113 make removal of the saddle 111 from the nozzle 105 easy and handy, whereupon the nozzle may readily be removed by lifting, and whence air automatically ceases to flow from the nozzle 105, or tend to flow into the passage 95.

Returning to the valve construction, the drawings (Fig. 2) show that the valve 87 is provided with a groove 115 adapted to register with the said inlet passage 95 and outlet passage 97 when the valve is in its maximum rearward and forward positions respectively. Hence, by positioning the valve 87 rearwardly, the exhaust passage 97 is closed, while the inlet passage 95 is opened whereby compressed air may pass from the line 107, through the open nozzle 105, open plug 103, passage 95 and groove 115, passage 101, passage 99 and to the cylinder 55, where work is done to press the piston 63 forwardly against the action of spring 73. By this means the plunger 51 is made to take a grease forcing stroke as hereinbefore described.

Next, by positioning the valve 85 forwardly, the groove 115 aligns with the exhaust passage 97, as shown in Fig. 2, whereupon the inlet passage 95 is closed. This action permits movement of air from the cylinder 55 through passages 99, 101, 97 and groove 115. Such movement of air is caused by the tendency of the air to re-expand and the expanding action of spring 73 which pushes the piston 63 rearwardly. The port 99 is near the bead 71 so that the cylinder 55 may be substantially emptied of air.

Movement of the piston 63 and rod 59 rearwardly results in an evacuating stroke of plunger 51, whereby the grease cylinder 27 is again reloaded as hereinbefore described.

In order to automatically position the valve 85 at its said maximum forward and rearward positions, so that pumping may be continuous when desired, the following full-stroke mechanism is used:

Vertically fastened to the driving rod 75 is fastened a driving bracket 117 adapted to slidably engage the valve stem 93. Springs 119 and 121 are placed over said stem 93 rearwardly and forwardly respectively. These springs 119 and 121 respectively engage the said head 91 and another head 123 of the stem 13. The bracket 117 engages the springs in its travel back and forth along the stem 93. It is obvious that upon engaging and compressing a spring to a given point, that the driving bracket (moving with the piston rod 59) will drive the valve rod 93.

In order to prevent the valve 87 from moving to reverse a given stroke of the piston 63 before the stroke is substantially finished, and to cause said valve to take a full stroke at every movement thereof, it is recessed at points 125 and 127. Corresponding points on the recesses are a distance apart equal to the distance between the passages 95 and 97.

Formed horizontally across the valve passage 85, at a point corresponding to the position of recess 125 when the valve 87 is in forward position, is a passage 129 (see Fig. 5). On each side of the valve 87 in the recess 125 is placed a ball 131. The balls are each backed by a compressed spring 133 reacting against a retaining plug 135. By this means the valve 87 may be resiliently held in either its exhaust or inlet position, depending upon which recess 125 or 127, the balls 131 are cooperating with.

When the driving bracket 117 moves 100 against the spring 119 (Fig. 2) and substantially compresses it, the rearward motion of the piston 63 is adapted to be about completed. In the meantime the recess 125 and balls 131 have caused the valve 87 not 105 to be moved, despite the partial compression of spring 119. Finally at or near the end of the stroke of piston 63, the spring is adapted to have been compressed enough to overcome the holding power of the balls 110 131, and the valve 87 moves under action of the spring 119. The valve must move rearwardly its full stroke, because as the high ridge 137 between the recesses 125 and 127 passes the balls 131, the inward movement of the balls into the recess 127 forces the valve to full stroke position as described, although the spring 119, may by this time have expanded to such a position that it would not, without the full stroke feature, be able to 120 move the valve to a position such that the groove 115 aligns with port 95. Of course, as the valve opens the inlet air port 95, the motion of the piston is reversed to a forward direction, and reversal of the above 125 events takes place. This time, however, the spring 121 comes into play, while spring 119 is idle. The reverse events will be obvious from the foregoing.

The pumping action by means of the 130

engine E is then continuously automatic as long as certain other events, to be described, take place. Of course when the nozzle 105 is removed from the engine E, no air is available to do work, and no grease is pumped to the line 49.

In order to control the pumping action of the device, the supply line 49 is provided with a manually operable valve V (Figs. 6, 10 7 and 9). This valve V may comprise any of numerous types. It has for its purpose merely the closing and opening of line 49 whereby pumping by the engine E is prevented, or permitted to take place, as desired. If the line 49 is positively closed, the air engine ceases to operate because grease cannot be ejected with the normal air pressure available. If the line is opened of course grease can pass and the air engine 15 automatically commences operation and continues operation until said line is again closed. The above described starting and stopping events can be initiated at substantially any stage of the cyclic action of the 20 engine E. If the engine is exhausting when valve V is closed the spring 73 continues forcing the piston toward the head 71, in so far as the rearward action of plunger 51, due to the check valve 29, is independent of conditions in line 49. The piston is then ready 25 for forward travel whenever the line 49 is opened to permit the predetermined air pressure in line 107 to take effect. The fact that the air engine can be stopped by closing 30 valve V does not imply that only low grease pressures are attainable in the outlet line 139 leading from the valve, for if the said line 139 is connected with nearly clogged bearings, several thousand pounds per square 35 inch of pressure may be brought to bear on the obstruction with only a nominal air pressure in cylinder 55. This is due to the ratio of the diameters of piston 63 and plunger 51. The closing of valve V, however, resists the high pressure. The valve V, for 40 example, may comprise the device shown in Figs. 6 and 7. This embodies in one unit, a grip 141 into which is screwed an inlet pipe 143 adapted to connect with the said line 49 from the grease pump. The grip 45 141 forms part of a casting 145 which is bored to slidably receive a hollow cylinder 147. The cylinder 147 may be used to deliver grease, or a proper line and feeding tip 50 may be connected thereto, depending upon the type of greasing service contemplated. The said outlet 139 forms part of the cylinder 147.

Forced tightly against a shoulder of the 55 cylinder 147 is a flange 149 upon which are fastened a pair of sidewardly extending headed gudgeons 151.

The gudgeons 151 engage a hand trigger 153. The trigger 153 engages a connecting link 155 at the top of the valve, which link

155 is pinned to vertical lugs 157 cast with the piece 145. A stop 159 prevents excessive motion forward of the trigger 153.

It is obvious from the foregoing that forward and backward movement of the cylinder 147 may be accomplished by moving the trigger forward and backward.

A spring 161 reacting between a plug 163 screwed into the casting 145, and the cylinder 147, normally holds the cylinder forward when the trigger is released to assume its dotted line position shown in Fig. 6. When the trigger is drawn rearwardly to its solid line position, the cylinder 147 is pulled rearwardly against the pressure of spring 161 whereby a lateral passage 165 in the cylinder aligns with a passage 167 in the casting 145. The passage 167 communicates with the pipe 143 and line 49. Hence when the trigger is drawn rearwardly, the valve V is open and, as described, the air engine E begins to pump grease. When the trigger is released the passages 165 and 167 are disaligned by means of spring 161 and the valve is closed, whereupon the air engine cannot and will not act in regard to pumping of the grease. It is now evident that control of the air engine and therefore control of the grease flow is had from the valve V.

Fig. 9 indicates a complete assembly of the apparatus and illustrates in dotted lines how the delivery line 49 is laid away in the horns or clips 15 when not in use. The apparatus may be towed about by means of the forward handle-bar 21, or carried by means of the upward handle 17. Movement from one air line, such as line 107, to another like one is readily accomplished merely by loosening one line and applying the other. No manually operable valves can be left open. The device is simple in application in so far as there are only obvious operations to be performed by an operator.

In view of the above, it is believed that the various features of this invention will be clear without further elaboration, and it will be seen that with the apparatus herein described, the several objects of the invention are achieved and other advantageous results attained.

As many changes could be made in carrying out the above construction without departing from the scope of the invention, it is intended that all matter contained in the above description or shown in the accompanying drawings shall be interpreted as illustrative and not in a limiting sense.

I claim:

1. A grease pump comprising side rails, a driving engine fastened to the rails at one set of ends and a plunger pump fastened thereto at the other ends whereby the rails are held together, a grease chamber fastened to the pump and means for operatively connecting said engine and pump,

comprising a connection adapted to allow for misalignment between the engine and pump.

2. A grease pump comprising a plunger cylinder, a reciprocating plunger therefor adapted to eject grease from said cylinder, a grease supply chamber associated with the said cylinder, a single acting air engine for reciprocating the plunger comprising, a cylinder, a piston therein and a spring behind the piston, the piston being adapted to move in one direction upon expansion of air on one side thereof, and to move in the reverse direction under action of the spring and a full-stroke valve for controlling the air supply to the cylinder, operable by the movement of the piston.

3. A grease pump comprising a cylinder, a reciprocating plunger therefor, adapted to eject grease from said cylinder, a grease supply chamber associated with said cylinder, an air engine for reciprocating the plunger comprising, a cylinder, a piston therein and a spring behind the piston, the piston being adapted to move in one direction upon expansion of air on one side thereof, and to move in the reverse direction under action of said spring, and a valve gear associated with the engine adapted to make the engine automatically operable as air is fed thereto.

4. A pump for fluids comprising ejecting means, a movable member for said ejecting means adapted to eject fluid therefrom, a fluid supply chamber associated with said

ejecting means, an air engine for moving said movable member comprising a cylinder, a piston therein and resilient returnable means behind the piston within said cylinder, the piston being adapted to move in one direction for expansion of supplied air on one side thereof, and to move in the reverse direction under action of said resilient means and valve-operating means associated with the engine adapted to make the engine automatically operable as air is supplied thereto.

5. A pump for fluids comprising a cylinder, a reciprocating plunger therefor adapted to eject fluid from said cylinder, a fluid supply chamber associated with said cylinder arranged at right angles thereto, an air engine for reciprocating the plunger comprising a cylinder substantially aligned with said plunger, a piston in said cylinder and a spring behind the piston within said cylinder, the piston being adapted to move in one direction upon expansion of air on one side thereof, and to move in the reverse direction under action of said spring, and a valve gear associated with the engine adapted to make the engine automatically operable as air is fed thereto, said cylinder and plunger being positioned substantially horizontal.

In testimony whereof, I have signed my name to this specification this 30th day of November, 1925.

FRANK S. BARKS.
